UNITED STATES PATENT OFFICE.

EDWARD R. TRACHY AND JOHN NELSON, OF MINNEAPOLIS, MINNESOTA; SAID NELSON
ASSIGNOR TO SAID TRACHY.

SANDING ATTACHMENT FOR AUTOMOBILES.

Application filed August 28, 1922. Serial No. 584,769.

To all whom it may concern:

Be it known that we, EDWARD R. TRACHY and JOHN NELSON, citizens of the United States, residing at Minneapolis, in the 5 county of Hennepin and State of Minnesota, have invented certain new and useful Improvements in Sanding Attachments for Automobiles, of which the following is a specification.

10 Our invention relates to sanding attachments for automobiles, and an object is to provide a device by means of which the driver of the car can quickly deposit sand in front of the driving wheels when the car 15 starts to skid on slippery surfaces, thereby checking the skidding action.

The full objects and advantages of our invention will appear in connection with the detailed description, and the novel features 20 of our inventive idea will be pointed out in the claims.

In the accompanying drawings which illustrate the application of our invention in one form in which it may be embodied, Fig. 25 1 is a side elevation partly broken away showing the device applied to an automobile. Fig. 2 is a view in vertical section on the line 2—2 of Fig. 1. Fig. 3 is a view in vertical section on the line 3—3 of Fig. 30 4. Fig. 4 is a view in vertical section on the line 4—4 of Fig. 3. Fig. 5 is a view in vertical section on the line 5—5 of Fig. 3.

In the drawings, our device is shown applied to an automobile having the customary 35 floor 10, dash 12, instrument board 14, and running boards 15. A casing 16 which constitutes a sand box is secured to the under- side of the floor 10 by brackets 18. This casing has a neck 20 extending through the 40 floor 10 by means of which the casing may be filled with sand, the neck being provided with a closure 22 which when in place is flush with the upper surface of the floor as shown in Fig. 1. Secured by screws 24 to 45 the two running boards 15 on opposite sides of the car are sand receptacles 26 into which extend pipes 28 leading downwardly from the opposite ends of the casing 16. The two receptacles 26 are alike and hence a detailed description of one of them will suffice. As shown in Fig. 3, the rear wall of the receptacle 26 stops short of the bottom thereof so as to provide a discharge slot 30. This rear wall in conjunction with a partition 50 55 32 depending from the top of the re-

ceptacle 26 forms a valve chamber, it being noted that the partition 32 stops short of the bottom so as to provide a passageway 34. A rotary valve 36 is mounted in the valve chamber, this valve being cut away on one side to form a flat portion 38. When the valve is in the position shown in Fig. 3, it is closed, and when rotated in the direction of the arrow so as to bring the flat portion downwardly, sand will be permitted to flow 60 out of the discharge slot 30. The two valves are secured by set screws 40 to a rod 42 rotatably mounted in bearings in the side walls of the two receptacles 26. Secured to the rod 42 is a sprocket wheel 44 over which 65 passes a section of sprocket chain 46 the ends of which are secured to crossed cables 48 and 50 which after passing around pairs of guide sheaves 52, 54, and 56 are secured to a hand lever 58 which is supported in 70 a suitable manner as by pivoting it to the instrument board 14.

The operation and advantages of our invention will be obvious in connection with the foregoing description. When the automobile starts to skid on slippery surfaces, the driver may almost instantaneously deposit sand in front of the driving wheels by pulling back on the hand lever 58. A pull 80 on this lever causes the two valves 36 to rotate in the direction of the arrow and open the valves so that sand will flow upon the roadway in front of the driving wheels as indicated in Fig. 1 thereby quickly stopping the skidding movement. Thereupon the 85 driver may push the hand lever forwardly in order to check the flow of sand. It will be understood that to get the best results, the sand should be dry and of substantially uniform size.

95 We claim:

1. A sanding attachment for automobiles comprising a container for sand, receptacles positioned in front of the driving wheels, pipes leading downwardly from said container to the forward portion of said receptacles, said receptacles each having a chamber formed by the rear wall thereof and a partition therein, said wall and partition stopping short of the bottom of the 100 receptacle to form discharge slots, a rotary cylindrical valve in said chamber said valve being flat on one side, and operating means within reach of the driver whereby said 105 valves may be partially rotated to bring 110

their flat portion either adjacent the bottom of said receptacles or adjacent said partitions.

2. A sanding attachment for automobiles comprising a container for sand, shutoff devices connected with said container and positioned in front of the driving wheels, a rotatable rod to which said shutoff devices are secured, a sprocket wheel secured to said rod, a section of sprocket-chain passing around said sprocket wheel, cables secured to the ends of said sprocket-chain, and operating means within reach of the driver to which said cables are attached.
- 10 3. A sanding attachment for automobiles

comprising a container for sand, shutoff devices positioned in front of the driving wheels, pipes leading downwardly from said container to said shutoff devices, a rotatable rod to which said shutoff devices are secured, a sprocket wheel secured to said rod, a section of sprocket chain passing around said sprocket wheel, cables secured to the ends of said sprocket chain, and a hand lever within reach of the driver to which said cables are attached.

In testimony whereof we hereunto affix our signatures.

EDWARD R. TRACHY.
JOHN NELSON.
